OR D 11,480

No. 11,480

November 4, 1879

UNITED STATES PATENT OFFICE.

FRANK S. BISSELL, OF PITTSBURG, PENNSYLVANIA.

DESIGN FOR GRATE-FRONTS.

Specification forming part of Design No. **11,480**, dated November 4, 1879; application filed August 22, 1879.
[Term of patent 7 years.]

To all whom it may concern:

Be it known that I, FRANK S. BISSELL, of Pittsburgh, in the county of Allegheny and State of Pennsylvania, have invented a new and original Design for Grate-Fronts; and I do hereby declare the following to be a full, clear, and exact description thereof, reference being had to the accompanying photographic illustration, forming a part of this specification, which represents a face view of the same.

My improved design consists of the ornamental border extending around the inner edge or arch of the grate-front, and the triangular ornamentations in relief in the two upper corners thereof, all as shown in the photographic illustration, and hereinafter described.

Around the inner edge or arch of the grate-front is formed the ornamental design composed of a series of triangles, *a a*, the base-lines of which form a continuous line around the edge of the grate-front, and of a series of cones, *b b*, the apexes of which extend inwardly between the angles of the series of triangles.

In each of the upper corners of the grate-front is formed a right-angle triangle, *c c*, in relief, the hypotenuse or base line *d* of which is curved to conform to the arch of the grate-

front, the whole being surrounded with a series of scallops. The face of the triangle is grooved or countersunk in such manner as to form two smaller triangles, *e e*, extending from the base-line of the larger triangle and joining in the center of said line, and a shield-like ornament, *i*, projects from their junction into the corner of the larger triangle.

What I claim as my invention, and desire to secure by Letters Patent, is—

1. The design for grate-fronts, consisting of the ornamental border around the inner edge or arch thereof, composed of the series of cones and triangles and the triangular corner-pieces in relief, the whole being ornamented substantially in the manner shown and described.

2. The design for grate-fronts, consisting of the ornamental border around the inner edge or arch thereof, composed of the series of cones and triangles, substantially as shown and described.

In testimony whereof I, the said FRANK S. BISSELL, have hereunto set my hand.

FRANK S. BISSELL.

Witnesses:

HENRY M. BISSELL,
JAMES I. KAY.
